HERMANN MALLICKH, OF DUREN, GERMANY.

PULPING MACHINE.

Application filed May 17, 1927, Serial No. 191,960, and in Germany June 21, 1926.

This invention relates to pulping machines for paper mills. It is well known that the amount of material that is reduced to pulp by a pulping machine increases with the width of the rotary pulping cylinder. For this reason attempts have been made to increase the output of pulping machines, having a container or tank with two pulp channels or races, by increasing the width of the cylinder. The width of the cylinder, which usually amounted to only 0.8 of its diameter was increased up to 1.2 of its diameter. But the desired effect could not result by thus increasing the width of the cylinder, because as this width, and width of the pulp race that depends thereon, increases, the distance of travel of the pulp at the outer edge of the race is also lengthened. Consequently the degree of slope or inclination of the bottom of the race at its outer edge becomes so small that the pulp stagnates thereat, or flows much slower than the pulp at the inner edge or wall of the race, so that the outer portion of the grinding cylinder or cutter cylinder has but little effect. The crosswise mixing of the pulp, when its consistency where it is led in is thick, is unsatisfactory in consequence of the large width of the cylinder and pulp race of such machines, and a drawback which results therefrom is that the pulp that circulates quickly at the short middle wall of the race is unduly shortened and squashed, while the fibres that pass along the long outer wall of the race are ground insufficiently and remain long.

The object of the present invention is to overcome these drawbacks. This is accomplished by making the cylinder roll or cutter cylinder of a paper pulp mill provided with two pulp races wider than the tail race leading from the cylinder and by arranging the cylinder so that its outer end stands or juts out beyond the outer edge of the tail race. At the outstanding part of the cylinder the pulp is thrown back over the top of the cylinder and led into a part of the race whence it is conducted to the head race. By this arrangement a much greater output is obtained through considerably increasing the width of the cylinder of the pulping machine. A thorough crosswise mixing of the pulp is effected, and as the width of the cylinder is greater than that of the adjoining tail race no areas outside the pulp current are formed where the pulp stagnates and which spoil the quality of the milled pulp.

A constructional form of the invention is illustrated in the accompanying Figs. 1 to 3 in which

Fig. 1 is a section on the line A—B of Fig. 2,

Fig. 2 is a top view in which the hood above the pulping cylinder is removed and

Fig. 3 is a section of the paper pulp machine on the line C—D of Fig. 2.

In the basin or tank *a* is journaled a grinding cylinder *b* whose width is about 1.2 of its diameter. The width of the ridge *c* and of the part of the tail race *d* adjoining the cylinder is about $\frac{2}{3}$ of that of cylinder or about 0.8 of its diameter. The cylinder is arranged in the tank so that the third of its width, by which it exceeds the width of the tail race *d*, stands out beyond the outer wall of the tail race. The wall *e* of the tank directly adjoins the outstanding part of the cylinder *b*. By arranging the cylinder *b* in this way only $\frac{2}{3}$ of the breadth of the pulp stream are conducted over the low ridge *c* into the tail race *d* which merges in the usual manner and width into the lateral returning race *f*. As the width of the race *d* amounts to $\frac{2}{3}$ of that of the cylinder or to 0.8 of its diameter the normal, desirable slope or inclination of the race bottom is obtained at the outer wall of the races *d* and *f*. The remaining third of the width of the pulp stream is thrown back over the top of the outstanding part of the cylinder *b* into the race at the front of the cylinder, this path of the backwardly thrown pulp being determined by the closed hood *g*. The third of the pulp stream thus thrown to the front of the cylinder *b* goes into the channel *h* which extends parallel to the cylinder axis. The channel *h* is formed or placed in the hood *g* and conducts the pulp down a slope through the middle wall of the tank or basin to the inner side of the race *f*. This returning race *f* widens out at the point where the pulp that is thrown back over the top of the cylinder is conducted into it. Therefore the cross-section of the returning race is sufficient to accommodate the two recombined pulp streams without any congestion taking place. By the aforescribed peculiar manner (shown by arrows in Fig. 2) of leading to the inner wall of the returning race *f* the part of the pulp stream that passes along the outer wall

2

of the tank, a very quick and effective cross-wise mixing of the pulp is accomplished. Furthermore the lengths of travel of the different pulp streams are perfectly equalized and the rate of their circulation increased, so that a grinding or pulping effect of the pulping machine is obtained which is much greater than in a machine of the ordinary design equipped with a cylinder of the same width but much larger diameter. As the outer wall *e* directly adjoins the part of the cylinder *b* where the pulp is thrown back over the top of the cylinder, no areas are formed beyond the rear of the cylinder which lie outside the pulp stream and in which a part of the pulp might stagnate.

To prevent losses through eddies in the part of the pulp stream that is thrown back over the cylinder, a smooth guide member *i* of sheet metal is arranged to extend concentrically around the part of the cylinder *b* located in the upper part of the closed hood *g*. The sheet metal guide *i* is attached at one end by a screw *k* or the like, located approximately in a horizontal plane through the middle of the cylinder, to the upper portion of the removable hood *g*. The other end of the guide *i* is free so that it can flex freely to and fro above the top of the cylinder *b*. One or more screw-threaded spindles *l* are riveted in the guide *i* which have nuts *m* that rest against small supports *n* fixed to the hood *g*. By this means the flexible sheet metal guide *i* can be held suspended at any desired adjustable distance above the periphery of the cutter cylinder. Surrounding the spindles *l* are helical springs *o* whose one end abuts upon the top of the guide *i* and whose other end presses against the supports *n*, so that the sheet metal guide *i* is held at a certain distance from the cylinder against the centrifugal action of the pulp flung up therefrom. Furthermore the helical springs allow the sheet metal guide *i* to

yield in an upward direction in case the cylinder should, for some reason or another, fly upwards.

I claim:

1. A pulping machine comprising a tank 50 having a head race and a tail race formed therein, a revolving pulping cylinder that is wider than the tail race leading from it and arranged to stand out beyond the outer wall of the tail race, and means for conducting material being pulped over the top of said outstanding part of the cylinder and in a direction parallel to the axis of the cylinder to the head race. 55

2. A pulping machine comprising a tank 60 having a head race and a tail race formed therein, a revolving pulping cutter cylinder that is wider than the tail race leading from it and arranged to stand out beyond the outer wall of the tail race, means for conducting material being pulped over the top of said outstanding part of the cutter cylinder and in a direction parallel to the axis of the cylinder to the head race, a hood above said cylinder, and an adjustable sheet metal guide 65 member between said hood and the periphery of said cylinder. 70

3. A pulping machine comprising a tank 75 having a head race, tail race and returning race, which joins the tail race to the head race, formed therein, a revolving pulping cylinder that is wider than the tail race leading from it and arranged to stand out beyond the outer wall of the tail race, and means 80 for conducting material being pulped over the top of said outstanding part of the cylinder and in a direction parallel to the axis of the cylinder into said returning race, the returning race being widened at the point where it receives pulp from said outstanding 85 part of said cylinder as and for the purpose set forth.

In testimony whereof I have signed my name to this specification.

HERMANN MALLICKH.
